(57) **CLAIM**

The ornamental design for pool cover as shown and described.

DESCRIPTION

FIG. 1 is an isometric view of pool cover showing my new design;

FIG. 2 is a front elevational view thereof of FIG. 1;

FIG. 3 is a rear elevational view thereof of FIG. 1;

FIG. 4 is a right elevational view thereof of FIG. 1;

FIG. 5 is a left side elevational view thereof of FIG. 1;

FIG. 6 is a top plan view thereof of FIG. 1;

FIG. 7 is a bottom plan view of thereof of FIG. 1; and,

FIG. 8 is an environment view of pool cover.

The broken lines are included for the purpose of illustrating features of the pool cover that form no part of the claimed design.

1 Claim, 5 Drawing Sheets
